UNITED STATES PATENT OFFICE.

GEORGE STEINGRUBER, OF HAZLEHURST, MISSISSIPPI, ASSIGNOR, BY DIRECT AND MESNE ASSIGNMENTS, OF TWO-THIRDS TO MINNIE B. STEINGRUBER, OF HAZLEHURST, MISSISSIPPI, AND ONE-THIRD TO BOLAN G. BRUMBY, OF MARIETTA, GEORGIA.

VAPORIZING ATTACHMENT FOR EXPLOSIVE-ENGINES.

1,266,077.

Specification of Letters Patent. Patented May 14, 1918.

Application filed March 25, 1916. Serial No. 86,747.

To all whom it may concern:

Be it known that I, GEORGE STEINGRUBER, a citizen of the United States, residing at Hazlehurst, in the county of Copiah and 5 State of Mississippi, have invented certain new and useful Improvements in Vaporizing Attachments for Explosive-Engines, of which the following is a specification.

The present invention comprises new and 10 useful means for facilitating the thorough vaporization of hydrocarbon fuel such as commonly employed in connection with the operation of internal combustion engines.

A primary object of this invention has 15 been to design an attachment susceptible of being employed in connection with ordinary types of explosive engines, and preferably utilized auxiliary to the customary carbureting means used, whereby the explosive 20 mixture after it has left the carburetor is caused to pass to a preheating chamber. In the preheating chamber the more or less effectively carbureted mixture is subjected to the action of peculiarly arranged and 25 formed heating tubes or members by which the mixture is effectively broken up and vaporized, whereupon it is permitted to pass to the cylinder or cylinders of the motor to be exploded in the customary manner.

Still another object of the invention has 30 been the provision of a means such as the attachment above generally described which does not require any material modification in the usual engine parts in order that the 35 invention may be adapted to the latter, the attachment comprising various chambers, tubular or pipe connections adapted to be readily combined with the usual carburetor, intake manifold and exhaust pipe parts, all 40 in a manner which will appear very fully upon reference to the following detail description and to the accompanying drawings, in which—

Figure 1 is a view partly in elevation and 45 partly in section showing the invention applied to the intake and exhaust manifold of an explosive engine and in connection with the carburetor for the latter.

Fig. 2 is a fragmentary horizontal sectional view taken about on the line 2—2 of Fig. 1.

Fig. 3 is a vertical sectional view taken about on the line 3—3 of Fig. 1.

Fig. 4 is a sectional view through one of

the vaporizing pipes or passages showing 55 the arrangement of the tubular baffles passing therethrough.

Fig. 5 is a section taken about on the line 5—5 of Fig. 1.

Fig. 6 is a sectional view of a modified 60 embodiment of the invention.

Fig. 7 is a sectional view of another modification of the invention.

Referring particularly to Figs. 1 to 5 inclusive of the drawings wherein a preferred form of my invention is illustrated, A denotes the ordinary intake manifold of an explosive engine and B the exhaust manifold, the former being disposed adjacent to a carburetor C of conventional 65 construction and connected therewith by peculiar means to be described. The exhaust manifold B is provided with openings 1 and 2 establishing communication between the same and the preheating chamber 3. The 70 preheating chamber 3 is seen best in Figs. 2 and 3, being formed at its bottom with the longitudinal seat which partially receives the intake manifold, the parts B and 3 being positively connected by couplings 4. A suitable 75 exhaust outlet pipe 5 extends from the preheating chamber 3 at a point approximately centrally of its ends.

Arranged within the preheating chamber 3 is the vaporizing pipe or passage 6 the 80 same consisting of a rebent pipe having branches 7 and 8 leading laterally and downwardly from the chamber 3, the lower terminals of the branches of the vaporizing pipe being connected in any suitable manner 85 with the separating chamber 9 which latter consists of a somewhat rectangular or box-like body formed with a horizontal partition 10. To the under side of the separator 9 is attached the pipe leading from the carburetor C, and to the upper side of the chamber 9 is attached the lower end of the intake manifold A. Any suitable means such as the flanges 11 and screws 12 are utilized to connect the parts just last mentioned. The purpose of the partition 10 is to divide the separator 9 into an inflow chamber 9^a and an outflow chamber 9^b to properly direct the carbureted fuel passing into the chamber 9^a from the carburetor C 100 to cause said fuel to pass upward through the branch pipe 7 into the vaporizing pipe or passage 6 from which the fuel in thor-

- oughly vaporized heated condition is caused to pass or return to the separator 9 at the outflow chamber 9^b with which chamber the intake manifold A is connected.
- 5 By reason of the location of the preheating chamber 3 in contact with the exhaust manifold B said chamber 3 is obviously heated effectively whereby to correspondingly heat the vaporizing pipe 6. To insure, however, the thorough breaking up and heating of the fuel constituents entering the vaporizing pipe 6 it is contemplated to locate at intervals throughout the length of said pipe 6 a series of tubular baffles 1^a 10 which baffles preferably comprise small copper tubes passing through the pipe 6 and the ends of which are swaged or clenched to establish the requisite air-tight connection between the baffles and the pipe 6. The baffles 1^a are preferably disposed in staggered relation to insure the impingement thereagainst of the fuel constituents entering the pipe 6, and the exhaust gases pass through said baffles.
- 15 The operation of the invention as above described will be evident but may be said to consist in the passage of the carbureted fuel through the chamber 9^a, branch pipe 7, into the vaporizing pipe 6 located in the preheating chamber 3, from which the thoroughly vaporized mixture in gaseous form is led through the pipe 8 to the outflow chamber 9^b of the separator 9 and from thence to the intake manifold A to be supplied to the cylinders of the engine in the customary manner.
- In Fig. 6 a modification of the invention is disclosed wherein the inflow chamber 9^x of the separator is connected with a branch pipe 7' leading to one end of the vaporizing pipe 6', the latter being mounted in the preheating chamber 3'. The vaporizing pipe 6' in this instance is a straight pipe supplied with the tubular baffles of the description previously set forth, said pipe being connected with the branch pipe 7' at one end, and the opposite end connected with the branch pipe 8', the latter leading to the outflow chamber 9'' of the separator.
- 20 In this instance the intake manifold is connected at its lower end with the outflow chamber 9'' at a point centrally of the ends of the separator. The exhaust outlet pipe 5' is connected with the preheating chamber 3' and the latter is supported on the exhaust manifold in the same manner as previously described. The ends of the preheating chamber 3' are closed by detachable bushings 13 through which the vaporizing pipe 6' passes.
- 25 Still another, and the most simple, embodiment of the invention is illustrated in Fig. 7. In this instance the preheating chamber 3^x surrounds the lower portion of the intake manifold and is heated by means

of the exhaust pipe connection 14. The lower portion of the intake manifold A is provided with the horizontal tubular baffles for breaking up the carbureted fuel for the purposes of thorough vaporization, after the manner of the formation of the parts 6 and 6' previously described. The exhaust outlet pipe is shown at 15 as leading from the lower portion of the chamber 3^x. For certain types of motors, and under certain conditions of service operation, the simple embodiment of the invention just described will afford a far more economical usage of fuel than obtainable incident to the employment of a carburetor alone.

In relation to the tubular baffles used in each adaptation of my invention above described, it is to be noted that these baffles while disposed in parallel planes pass transversely through the vaporizing pipe so as to intersect, practically speaking, the axis of said pipe, by which is meant the longitudinal axial center of the pipe. Furthermore, these baffles may not only be characterized as staggered as previously mentioned, but are disposed at angles to one another so that from the standpoint of efficiency of the breaking up action of the baffles in respect to the ingredients of the explosive fuel, a most advantageous structure is obtained.

Having thus described the invention, what is claimed is:

1. In combination with the intake and exhaust manifolds of an explosive engine, a vaporizing and preheating attachment comprising a preheating chamber detachably positioned upon the exhaust manifold so as to be heated by the latter, fuel supply means connected with the intake manifold, a separator interposed between said fuel supply means and the intake manifold, said separator comprising a partition dividing the same into an inflow chamber communicating with the fuel supply means, and an outflow chamber communicating with said intake manifold, vaporizing means disposed in the preheating chamber and communicating connections intermediate said vaporizing means and the inflow and outflow chambers of said separator.

2. In combination with the intake and exhaust manifolds of an explosive engine, a vaporizing and preheating attachment comprising a preheating chamber detachably positioned upon the exhaust manifold so as to be heated by the latter, fuel supply means connected with the intake manifold, a separator interposed between said fuel supply means and the intake manifold, said separator comprising a partition dividing the same into an inflow chamber communicating with the fuel supply means and an outflow chamber communicating with said intake manifold, a vaporizing pipe disposed in said preheating chamber, a branch pipe connect-

ing one end of the vaporizing pipe with the inflow chamber of the separator, and a second branch pipe connecting the other end of the vaporizing pipe with the outflow chamber of the separator.

3. In combination with the intake and exhaust manifolds of an explosive engine, a vaporizing and preheating attachment comprising a preheating chamber detachably positioned upon the exhaust manifold so as to be heated by the latter, fuel supply means connected with the intake manifold, a separator interposed between said fuel supply means and the intake manifold, said separator comprising a partition dividing the same into an inflow chamber communicating with the fuel supply means and an outflow

chamber communicating with said intake manifold, a vaporizing pipe disposed in said preheating chamber, a branch pipe connecting one end of the vaporizing pipe with the inflow chamber of the separator, a second branch pipe connecting the other end of the vaporizing pipe with the outflow chamber of the separator, and coupling members intermediate the opposite ends of the preheating chamber and the exhaust manifold and establishing communication between the manifold and preheating chamber whereby the exhaust gases are adapted to circulate through the preheating chamber.

In testimony whereof I affix my signature.

GEORGE STEINGRUBER.
